SURFACE ACTIVE COMPOSITION AND
METHOD OF MAKING

James M. Johnson and Francis L. Mark, New York, and Murray Jelling, Brooklyn, N. Y., assignors to Nostrip Inc., a corporation of Delaware

No Drawing. Application October 31, 1947,
Serial No. 783,444

8 Claims. (Cl. 260—97.5)

1

This invention relates to a surface active agent and the method of making it. It relates also to asphalt and like bituminous compositions including the agent as an additive.

The invention is particularly useful in making improved paving compositions, as, in improving the coating of wet stone by bituminous materials, bonding of the materials to the stone, and resistance to separation after long soaking in water. It will be illustrated, therefore, by description in connection with such use.

The invention relates to additives of the class described in the following patents to James M. Johnson: No. 2,426,220, issued August 26, 1947; No. 2,386,867, issued October 16, 1945; and No. 2,419,406, issued April 22, 1947.

Our new product is flowable as first made. When cold it remains flowable when mixed with only a small proportion of solvents such as relatively inexpensive petroleum or coal tar distillate products while maintaining effectiveness of the additive in asphalt compositions.

Briefly stated, our invention comprises the method of making an amido-amino-amine soap by reacting a polyamine containing at least 3 amino groups with an acid mixture consisting essentially of higher fatty acids and rosin acids, in proportion to leave unreacted at least one amino group of the amine, and then heating the resulting amine soap at an elevated temperature causing decomposition of the soap group of the higher fatty acid with the amine, so as to form an amido group and leave the soap of the rosin acid in undecomposed condition.

The invention includes also the amido-amino-amine soap in which the amido group includes the acyl radical R.CO. of a higher fatty acid and in which the acid radical represented in the amine soap is that of a rosin acid such as abietic.

The invention comprises, in addition, compositions of bituminous paving material including the above mentioned product as additive, as, for instance, an asphalt composition including 0.2 to 0.7 part of the soap to 100 parts of the asphalt, preferably with a diluent of kind to be described.

The invention will be illustrated in greater detail by description in connection with my preferred surface active agent, namely, oleyl amido-amino-amine abietate, the amine serving as the base for this compound being diethylene triamine.

In making this compound, 1 mol of diethylene triamine is mixed with 1 mol of oleic acid and 1 mol of abietic acid. The mixture is then heat-

2

ed. Reaction occurs in accordance with the following equations, R.COOH and R'.COOH representing, respectively, oleic acid and abietic acid

In the first of the above reactions, there is formed the disoap (A) of the oleic acid and the abietic acid. In the second reaction, which is produced by controlled heating, water is evolved from the oleic acid soap group at the left in the formula as written. This group is decomposed to the amide group R.CO.NH. We have discovered that the abietate soap is not decomposed at a temperature as low as that which is adequate to decompose the oleic acid soap; we select such temperature for this heating that the abietate soap remains in undecomposed condition. This gives a finished product that contains the oleic acid amide, the abietate soap, and a free amino group such as the NH. shown the Formula B above.

The decomposition of the disoap first formed into the amido-amino-amine soap desired is followed by titration of specimens of the mixture being heated. This titration is made with a standard aqueous solution of sodium hydroxide with phenolphthalein as the indicator. The soap groups which remain, as for instance, NH_2.OOC.R', titrate as so much free acid whereas the amido group R.CO.NH. is not saponifiable. The decomposition reaction is considered to be complete to the desired step when 1 mol of the sodium hydroxide will neutralize, that is, saponify, 1 mol of the amido-amino-amine soap.

The reaction may be followed approximately by the proportion of water eliminated, although this control is not entirely accurate and may be misleading, because the escape as vapor of the liberated water is retarded by retention of the water in the soap, possibly by hydrate formation.

The presence and the proportion of the amino and soap groups remaining in the formula for the product are shown by titration of the soap with standard hydrochloric acid or like acid with methyl orange as the indicator. One mol of the product which includes 1 unreacted or free amino group (NH₂) and 1 soap group (NH₂OOC.R') will, in this titration, require 2 mols of hydrochloric acid.

The Formula B above may be considered as the type formula for our improved product, RCO.

in the type formula representing the acyl group of the higher fatty acid, that is the higher fatty acid molecule less one hydroxyl group, and the R'.COO. group representing the radical of a rosin acid, that is, such acid less the hydrogen of the carboxylic acid group.

A more general type formula for our amido-amino-amine soaps is the following:

In this formula, R.CO. and R'.COO. have the same meaning as above; X represents the residue of a polyamine containing originally 3 to 6 amine groups, the residue being the amine less 2 amine groups and preferably less 2 primary amine (NH₂) groups. Examples of such residues represented by X are

Examples of higher fatty acids that may be used as the R.COOH of Equation 1 above and to furnish the acyl radicals R.CO. of compound (B) are oleic, linoleic, linolenic, and lauric acid.

As the rosin acid to furnish the molecule R'COOH in Equation 1, we used abietic acid, rosin, the rosin acid fraction of talloil, or the like.

As the amine used, diethylene triamine is shown in Equation 1 above. In place of this amine, we may substitute, on either a mol for mol or an equal weight basis, triethylene tetramine, tetraethylene pentamine, dipropylene triamine, tributylene tetramine, pentaethylene hexamine and the like polyamines containing 3 to 6 or so amine groups to the molecule.

As the diluents we prefer light petroleum fuel oil such as No. 2 having a relatively high aromatic content. In place of the fuel oil, we may use, however, an equal proportion by weight of coal tar diluents such as creosote, xylol, or toluol, or other coal tar, wood tar, or shale oil distillate.

The selected organic acids and the polyamine used in forming the soaps as shown in Equation 1 are mixed in liquid condition at room temperature or at elevated temperatures as required to melt any normally solid ingredient, say at 80°-100° C.

For effecting the partial dehydration according to Equation 2, there is used a temperature adequate to decompose the fatty acid soap without decomposing the rosin acid soap group. Thus there is used to advantage temperatures within the range 90° to 100° C. and preferably about 110° to 150° C. At the lower temperatures within the above ranges the reaction is slow and is difficult to complete in a period of time that is satisfactory commercially.

It is to be understood that reactions (1) and (2) may be made to occur at the same time. In fact, we preferably make these two reactions simultaneously. Thus we mix the selected higher fatty and rosin acid with the amine at a temperature of about 90° to 100° C. Under these conditions, the heat of reaction of the organic acids with the amine raises the temperature to about 120°-125° C. or so, the exact temperature depending upon the size of the batch and other commercial conditions affecting heat loss. At this higher temperature the disoap, formed as in Equation 1 above, undergoes decomposition to the amido-amino-amine soap of Formula B.

As to proportions, the organic acid mixture is

used in proportion less than that required theoretically to react with all of the amine groups of the selected amine. When the amine used is a triamine, as, for instance, diethylene triamine, then there is used a total of about 2 mols of the mixed organic acids for one of the amine. When the amine used is a tetramine, then there are used not more than 3 mols of the organic acids and preferably about 2.5 to 2.9.

- 10 When a pentamine is used, the proportion of the acid is not over 4 mols and preferably about 3.5 to 3.8. In the case of talloil having an acid value of 168 and an average molecular weight of 334, we use 6.5 parts by weight to 1 part by weight of diethylene triamine. With the tetramine and pentamine, we keep this same weight ratio of 6.5 parts of the selected mixed organic acids to 1 part of the amine.

- Except as specifically stated to the contrary, 20 all proportions are expressed herein as parts by weight.

It will be noted that, in our method and composition, the acid used consists essentially of the higher fatty acid and rosin acid. It is not

- 25 required to use any other acid in addition. With only a very limited dilution of our product with petroleum fuel oil or other suitable liquid diluent, we make homogeneous, readily flowable solutions that may be withdrawn from tank cars or drums 30 without applying any external heat and that are readily incorporated into heated or cut-back bitumen.

By contrast we have made from the polyamine and the acid mixture consisting essentially of

- 35 the higher fatty acids and rosin acids, surface active agents in which there was not the combination of unreacted amine group, fatty acid amide, and a rosin acid soap. The product so made did not give a readily flowable liquid unless there was present an additional large excess of acids as diluent.

Example 1

One mol of oleic acid and 1 mol of abietic acid 45 are heated at 90°-95° C. until the entire material is in the fluid state. Then 1 mol of diethylene triamine at 25° C. is added and the three reactants are mixed thoroughly. During the reaction the temperature rises to 120° to 125° C. 50 and the disoap is formed.

The material is then heated to 150° C. over a 55 period of 2 to 10 hours and held at 150° C. for about 1 hour. While the temperature is being raised, the oleic acid soap is decomposed and water is evolved, the oleic acid soap portion of the molecule being converted to the oleic acid amide.

The product is soluble in liquid hydrocarbons. When 6 to 9 parts of it are dissolved in 1 to 4

- 60 parts of fuel oil No. 2, the resultant product is a homogeneous liquid having an A. S. T. M. pour point of about 40° F. maximum. This solution also is effective as a surface active agent in asphalt, tar, and like bituminous composition, at 65 a concentration of 0.2 to 1 part for 100 parts of the said composition, the exact proportion required depending on the type and condition of the bitumen and of the mineral aggregate and also the method and type of construction in 70 which the mixture is to be used.

Example 2

The procedure of Example 1 is followed except that (a) 1 mol of linoleic acid is substituted for the 1 mol of oleic acid and (b) rosin is

substituted on the chemically equivalent basis for the abietic acid.

Example 3

The procedure of Example 1 is followed except that an amount of crude tall oil equivalent to 2 mols of acid is substituted for the oleic acid and abietic acid.

The crude tall oil or refined tall oil, the composition of which has not been radically changed in the refining process, is a particularly satisfactory material for the reaction. It consists of approximately 50% fatty acids and 50% rosin acids, thus supplying fatty acids and rosin acids known to contain substantial proportions of abietic acid.

Example 4

The procedure of Example 1 is followed except that the 1 mol of oleic acid is substituted by an equivalent weight of the mixed fatty acids of vegetable and animal oils as, for instance, cottonseed, cocoanut, linseed, or fish oil.

Example 5

In place of the fatty acid used in any of the numbered examples above, we substitute an equivalent weight of a fatty oil. Thus we may use in place of a mol of oleic or like acid, one-third of a mol of a vegetable or animal fatty oil such as cottonseed, cocoanut, linseed, or a fish oil. When such oils are used they are saponified by the amine, with the production of the compound shown in the Formula B above and glycerine as a by-product. It should be understood that one mol of rosin acids is used along with the fatty oils, to provide the acid shown in the Equation 1 as $R'COOH$.

Example 6

Any one of the surface active agents made as described herein or more particularly as described in Example 1-5 above is mixed with a flowable bituminous material in proportion to improve the adhesion of the material to sand, gravel, slag, stone, or like paving aggregate in either wet or dry condition. Thus there is used $\frac{1}{4}$ to 1 part of the surface active agent to 100 parts of asphalt, the exact proportion required depending upon the condition and type of aggregate which is to be bonded with the asphalt.

In any case, the bituminous material used is flowable, that is flowable at somewhat elevated temperatures or when cut back with a solvent. Examples of such flowable bituminous materials are native lake asphalt, asphalt cut back with a hydrocarbon diluent, petroleum still residues, and heavy coal tars.

When incorporated in such bituminous materials, our additive increases the adhesion of the bitumen to the aggregate whether the latter is incorporated wet or dry and in a pavement increases the stripping resistance and stability on long exposure to the weather. As compared to additives used heretofore, the product is cheaper for a given level of effectiveness in coating wet aggregates, resistance to stripping, and long range stability in the presence of moisture. It is flowable at summer temperatures, and on very slight dilution down to temperatures of 40° F.

It will be understood also that it is intended to cover all changes and modifications of the examples of the invention herein chosen for the purpose of illustration which do not constitute

departures from the spirit and scope of the invention.

What we claim is:

1. In making an amido-amino-amine soap in which the amide group is essentially derived from fatty acids and the soap group from rosin acids, the method which comprises forming a mixture of one mol of a polyamine containing 3 to 6 amino groups with organic carboxylic acids, the number of mols of acids used being at least 2 mols and not more than the number of amino groups less 1 and the acids consisting essentially of higher fatty acids and rosin acids, maintaining contact between the said acids and the amine until the acids are substantially completely reacted with the amine, with the production of fatty acid and rosin acid soap of the amine, and then heating the soap at a temperature of 90° C. to 180° C. until decomposition with the liberation of water converts a substantial part at least of the fatty acid soap present to an aliphatic amide, the rosin acid soap portion remaining in the product.
2. The method described in claim 1, the amine used being diethylene triamine and the acids used being, higher fatty acids and rosin acids, the proportion of higher fatty acids used being approximately 1 mol to 1 mol of the rosin acids.
3. The method described in claim 1, the temperature of heating being 110° to 150° C.
4. The method described in claim 1, the heating with the liberation of water being discontinued when titration with alkali shows that only approximately 1 mol of the 2 mols of acid originally used is titratable by the alkali.
5. As a new compound, an amido-amino-amine soap of the type formula $R.CO.NH.X.NH_3.OOC.R'$ in which $R.CO.$ represents the acyl group of a higher fatty acid, $R'.COO.$ represents the radical of a rosin acid, and X represents a polyamine containing normally 3 to 6 amino groups less 2 of the said amino groups.
6. As a new compound, an amido-amino-amine soap of the type formula $R.CO.NH.C_2H_4.NH.C_2H_4.NH_3.OOC.R'$

in which $R.CO.$ represents the acyl group of a higher fatty acid and $R'.COO.$ represents the radical of a rosin acid.

7. As a new compound an amido-amino-amine abietate of the type formula

$R.CO.NH.C_2H_4.NH.C_2H_4.NH_3.OOC.R'$

in which $R.CO.$ represents the acyl group of a higher fatty acid and $R'.COO.$ represents the abietate radical.

8. The compound described in claim 7, $R.CO.$ representing the oleyl radical $C_{17}H_{33}.CO.$
